UNITED STATES PATENT OFFICE.

CIRIACO GARCILLÁN, OF NEW YORK, N. Y.

ADVERTISING DEVICE.

1,374,005.

Specification of Letters Patent. Patented Apr. 5, 1921.

Application filed May 27, 1920. Serial No. 384,671.

To all whom it may concern:

Be it known that I, CIRIACO GARCILLÁN, a citizen of Spain, and a resident of the city of New York, borough of Manhattan, in the 5 county and State of New York, have invented a new and Improved Advertising Device, of which the following is a full, clear, and exact description.

The present invention relates to new and 10 useful improvements in signs, and it pertains more particularly to signs of the interchangeable letter type.

It is the primary object of the present invention to so construct a sign that the several letters thereof may be placed in display position and removed from display position at will.

It is a further object of the present invention to provide letter plates adapted to 20 be carried in such a manner as to display the letters thereon.

It is a further object of the invention to so construct a letter-supporting means that plates of various sizes may be used in connection therewith.

Referring to the drawings—

Figure 1 is a front elevation partly broken away of a sign constructed in accordance with the present invention;

30 Fig. 2 is a top plan view thereof;

Fig. 3 is a vertical sectional view taken on the line 3—3 of Fig. 1;

Fig. 4 is a detail perspective view of one of the letter plate securing means.

35 Referring more particularly to the drawings, the device comprises two bars 5 and 6, and these bars 5 and 6 are adapted to be arranged in spaced relation to each other. The top bar 5 is preferably of rectangular cross-sectional form, the lower bar 6, however, being provided with a right-angular flange 7 on its lower edge, and it is this flange 7 which is adapted to support the several letter plates 8.

45 The reference character 9 designates a letter plate retaining clip and said clip is provided on its upper edge with an integral sheet metal tongue 10 adapted to be bent over upon itself into parallelism with the 50 body portion of the clip 9.

The device is operated in the following manner:

The clips 9 with their integral tongues 10 bent backwardly upon the body portion of the clips are positioned upon the upper bar 55 5, and the lower bar 6. The letter plates 8 are then positioned with their lower edges resting upon the right-angular flange 7 of the lower bar 6, and the clips 9 are then positioned as shown in Fig. 1 with the side 60 edges of their body portions overlapping the adjacent letter plates 8.

It is to be understood that the clips 9 are carried by both the top bar 5 and the lower bar 6 in order that the letter plates 8 will 65 be maintained in proper spaced relation and against accidental displacement both at the top and at the bottom of the sign.

While in the present instance but two bars 5 and 6 have been shown, it is to be understood that the device may be constructed in the form of a rectangular frame with any number of cross bars, thus providing various letter spaces,

What is claimed is:

1. A device of the character described comprising a pair of spaced parallel bars, a plurality of letter plates carried by said bars, and detachable means embodying a clip having an integral tongue adapted to be 80 bent relative to the body portion of the clip and into engagement with the bars and having letter-plate-engaging means adapted to engage the letter plates and maintain them in proper position with respect to said bars, 85 substantially as described.

2. A sign comprising a pair of parallel bars arranged in spaced relation, a supporting shelf formed integral with one of said bars, a plurality of letter plates supported upon said shelf, and means for maintaining said letter plates in position between said parallel bars, said means comprising a plurality of substantially U-shaped clips carried by each of said bars in such a manner 95 as to overlie the ends of the plates to prevent their displacement relative to the bars.

CIRIACO GARCILLÁN.
